US00D748123S

(12) **United States Design Patent**
Schwengler et al.

(10) **Patent No.:** US D748,123 S
(45) **Date of Patent:** ** Jan. 26, 2016

(54) **DISPLAY SCREEN WITH GRAPHICAL USER INTERFACE**

(71) Applicant: **Symantec Corporation**, Mountain View, CA (US)

(72) Inventors: **Stefan Schwengler**, Miami, FL (US); **Len Toyoshiba**, San Jose, CA (US); **John Beckwith**, Oregon City, OR (US)

(73) Assignee: **SYMANTEC CORPORATION**, Mountain View, CA (US)

(**) Term: **14 Years**

(21) Appl. No.: **29/472,455**

(22) Filed: **Nov. 12, 2013**

Related U.S. Application Data

(63) Continuation of application No. 29/456,734, filed on Jun. 3, 2013, now Pat. No. Des. 696,690, which is a continuation of application No. 29/412,542, filed on Feb. 3, 2012, now Pat. No. Des. 683,745.

(57) **CLAIM**

The ornamental design for a display screen with graphical user interface, as shown and described.

DESCRIPTION

The sole FIGURE is a front view of a display screen with graphical user interface showing my new design.

The broken lines in the drawing represent portions of the display screen with graphical user interface that form no part of the claimed design.

1 Claim, 1 Drawing Sheet
